STEAM IRON CLOSURE AND LATCH

Joseph H. Cone, Bridgeport, Conn., assignor to
 Casco Products Corporation, Bridgeport, Conn.,
 a corporation of Connecticut

Application May 2, 1951, Serial No. 224,229

11 Claims. (Cl. 38—77)

1

This invention relates to steam irons of the type having a hinged handle structure movable between raised boiler filling position and lowered operative position, and more particularly to handle latching means and boiler closure means in such irons.

An object of the invention is to provide an improved steam iron of the above type, characterized by latching and stopper mechanisms which are greatly simplified and reduced in cost.

Another object of the invention is to provide an improved and simplified, inexpensive latching and stopper mechanism for a hinged-handle type steam iron, which is effective in operation and reliable throughout an extended period of use.

Still another object of the invention is to provide an improved steam iron with latching and stopper mechanism according to the foregoing, which is simple and convenient for a user to operate.

A still further object of the invention is to provide an improved combined unitary latching and stopper mechanism for a hinged-handle type steam iron.

I accomplish the above objects, in the embodiment of the invention illustrated herein by providing a boiler having a filler opening in its top and safety valve means separate from said opening, and having a hinged handle structure mounted to swing between an operative position overlying the boiler and filler opening and a raised boiler-filling position remote from the boiler. In combination with this structure I provide a simple combined unitary filler plug and manually operable latch means carried by the handle structure and a cooperable combined latch means and filler funnel on the boiler, to lock the handle structure to the boiler in operative position and to seal the filler opening thereof. By making the latch and stopper mechanism as a single, unitary device, separate from the safety valve, I am able to eliminate resilient mountings and the like and to further simplify the structure and avoid duplication of parts, thus reducing costs materially.

Preferably the combined latch means and filler plug unit is carried by the handle structure intermediate the front and rear posts thereof, and comprises a manually operable knob and a rotary shaft or post passing through the base portion of the handle structure and mounting at its lower end a stopper disk in position to seat against the filler funnel. The rotary post carries laterally projecting lugs disposed adjacent the stopper and engageable with camming shoulders mounted on

2

the upper rim portion of the filler funnel, the organization being such that latching of the handle structure in its operative position moves and holds the stopper disk in sealing position against the filler funnel.

I also provide cooperable stop means on the front post of the handle structure and on the body or casing of the iron, said stop means being brought into engagement as an incident to the latching operation and subsequent to a predetermined normal distortion experienced by the stopper disk as a result of the latching pressure. The cooperable stop means advantageously provides increased rigidity between the handle and body of the iron.

Other features and advantages will hereinafter appear.

In the accompanying drawings:

Figure 1 is a longitudinal vertical sectional view through an improved steam iron embodying the invention.

Fig. 2 is a fragmentary section taken on line 2—2 of Fig. 1.

Fig. 3 is a fragmentary vertical sectional view of the unitary latching and stopper mechanism in unlatched position.

Fig. 4 is a top or plan view of the filler funnel and opening of the boiler.

Fig. 5 is a fragmentary sectional view taken on line 5—5 of Fig. 4.

As shown, the steam iron of this invention comprises a sole plate 10 having an electric heating coil 11 controlled by a thermostat 12 which is adjusted through a shaft 13 and knob 14. In its forward position the sole plate 10 has a steam chamber 15 enclosed by a cover plate 16 to which a hollow stud 17 is screwed.

Above the sole plate 10 a boiler 18 is mounted, the forward portion of the boiler having baffles 19, 20 and 21 disposed about the stud 17, and having a steam dome 22 surrounding the upper end of a steam pipe 23 carried at its lower end by the stud 17. The boiler 18 is secured to the sole plate 10 by virtue of the stud 17 having a shoulder 24 engaging the bottom of the boiler and securing the same to the cover plate 16 of the steam chamber.

Enclosing the boiler 18 is a casing 25, said casing being secured to the forward top portion of the boiler 18 by means of a threaded bushing 26 functioning as a screw, on which the steam dome 22 is screwed. As is evident, the steam pipe 23 extends upward through the bushing 26 and into the dome a substantial distance.

As previously mentioned, the steam iron illus-

trated herein is of the type having a hinged handle structure movable between a lowered operative position (shown in Fig. 1) or a raised boiler-filling position (indicated by the fragmentary broken outline in Fig. 1). The hinged handle structure, indicated generally by the character 27, comprises a handle proper 28 carried by front and rear posts 29 and 30 respectively, mounted on a generally flat broad base portion 31 having a rear extension 32 pivotally fastened by means of pins 33 on the rear of the casing 25.

The front post 28 of the handle structure is made hollow to clear the steam dome 22, and the latter is provided with a boiler-emptying or discharge orifice 34 normally closed by a safety blowoff valve 35 spring mounted on the handle structure as illustrated. The combined steam dome, emptying means and safety valve shown herein form the subject matter of my copending application, Serial No. 221,650, filed April 18, 1951, entitled "Steam Iron."

In accordance with the present invention I provide, in combination with the handle structure 27 and boiler 18 a novel unitary combined stopper and latch mechanism, and provide a co-operable combined latch mechanism and filler opening on the boiler 18 to the end that a simplification and economy in the fabrication of the iron is effected while at the same time the handle structure 27 may be easily and securely locked in the lowered operative position and the boiler opening sealed, or just as easily and quickly raised to the filling position wherein the boiler opening is exposed and accessible for receiving water.

Accordingly, referring to Figs. 1, 4 and 5, a filler opening 40 is provided in the top wall of the boiler 18, said opening being defined by a funnel 41 having at its bottom a baffle or deflector 42. The upper edge or lip 43 of the funnel 41 is crimped around the top wall of the boiler 18, and supports a gasket 44 engaging the top wall of the casing 25. Above the funnel 41 the casing wall has an opening 45 defined by an upturned flange 46 provided with inwardly extended arcuate flanges or shoulders 47 disposed opposite each other and sloping as indicated in Fig. 5. The shoulders 47 have stop lugs 48 and are adapted to engage lugs or pins 49 of a co-operable latch means on the handle structure, to function as camming surfaces therefor.

As shown in Figs. 1 and 2, the base portion 31 of the handle structure is apertured to receive and rotatably carry a hollow post 50 mounting at its upper end a knob 51, the lower end of the post carrying a collar 52 through which the pins 49 extend. Preferably the pins 49 have flanges 53 to position them, and at their inner ends pass through the post 50 and into an annular groove 54 in a stud 55 carried in the post 50. At its lower end the stud 55 mounts a sealing disk 56 having a rim portion 57 of rubber or rubber-like material adapted to engage and seat in the funnel 41.

The disk 56 is non-yieldably carried by the post 50 but is rotatable with respect thereto. The positions of the disk 56 and pins 49 are so related with respect to the positions of the funnel 41 and camming shoulders 47, that when the handle structure 27 is in the lowered position of Fig. 1 the knob 51 may be turned, engaging the lugs 49 with the shoulders 47 and camming the disk 56 downward into sealing engagement with the funnel 41. In Figs. 1 and 2 the latch mechanism is shown in locking position, with the pins 49

brought to a halt against the stops 48. For this position the peripheral portion 57 of the sealing disk 56 is firmly held against the funnel 41 and is somewhat distorted under the pressure exerted by the latch mechanism.

Preferably co-operable stop means are provided on the casing 25 and front post 29 of the handle structure 27 to steady the handle when it is latched in operative position. This stop means comprises a washer 58 mounted under the bottom flange of the steam dome 22 to engage the under-surface of the front post 29 of the handle structure. Such engagement between the post 29 and washer 58 does not take place, however, until after the yieldable peripheral portion 57 of the sealing disk 56 has been distorted by the pressure exerted by the latch mechanism, such pressure forcing down the front portion of the handle structure until the post touches the washer 58.

During the rotary movement of the knob 51 and post 50 incident to latching the handle structure in its operative position, the sealing disk 56 remains stationary through its engagement with the stationary funnel 41, this being possible by virtue of the rotatable mounting of the stud 55 in the post 50.

By the above construction I have provided an extremely simple and economical-to-produce combined latch means and stopper assembly for an electric steam iron of the hinged handle type. Where heretofore two separate assemblies were required, one constituting the stopper for the filler opening and the other constituting the latch means, I now provide but a single assembly, thereby materially reducing the cost of the iron while at the same time maintaining high efficiency and reliability of operation.

It will be noted that the latching parts comprising the pins 49 and shoulders 47 are disposed closely adjacent and on opposite sides of the stopper disk 56 and filler funnel or valve seat 41. By such close spacing I am enabled to reduce to a minimum the effect of variations and tolerances in manufacture without resorting to resilient mounting means for the stopper or latch. Where, as in the prior art, the stopper and latch are widely separated, manufacturing variations in the dimensions of the components of the iron, particularly those mounting and supporting said parts, require that special provision be made for compensation, by the use of yieldable means, spring mountings and the like, adding to the cost of the assemblage. With the improved construction described above the effect of such variations is negligible and does not materially affect the relative positions of the parts when these are assembled in manufacture. Accordingly I am enabled to dispense with yieldable means, and can depend mainly on the yieldability of the peripheral portion 57 of the stopper disk 56 to provide an effective and smooth working latch and stopper mechanism.

Variations and modifications may be made within the scope of the claims and portions of the improvements may be used without others.

I claim:

1. In an electric steam iron of the type having a boiler with a filler opening at its top and a handle structure over the boiler, hingedly mounted for movement between a raised filling position exposing the filler opening and a lowered operative position overlying the filler opening, the combination with said handle structure and boiler of a combined unitary filler plug and manually operable latch means carried by said handle structure

and a cooperable combined latch means and filler opening on the boiler to lock the handle structure to the boiler in operative position and seal the filler opening thereof.

2. In an electric steam iron of the type having a boiler with a filler opening at its top and a handle structure over the boiler, hingedly mounted for movement between a raised filling position exposing the filler opening and a lowered operative position overlying the filler opening, the combination with said handle structure and boiler of a combined unitary filler plug and manually operable latch means carried by said handle structure and a cooperable combined latch means and filler opening on the boiler to lock the handle structure to the boiler in operative position and seal the filler opening thereof; and coengaging stops on the boiler and handle structure, maintained in engagement with each other when the latch means is operative to lock the handle structure in operative position.

3. The invention as defined in claim 1, in which the filler plug comprises a disk and in which the manually operable latch means includes a rotary post on one end of which the disk is carried, and includes a knob on the other end of the post.

4. The invention as defined in claim 3, in which the rotary post has laterally projecting locking lugs, and in which the latch means on the boiler comprises sloping shoulders disposed around the filler opening, engageable with the said lugs.

5. In an electric steam iron of the type having a boiler with a filler opening at its top and a handle structure over the boiler, hingedly mounted for movement between a raised filling position exposing the filler opening and a lowered operative position overlying the filler opening, the combination with said handle structure and boiler of a combined unitary filler plug and manually operable latch means carried by said handle structure; and latch means connected to the boiler and cooperable with said manually operable means to lock the handle structure in operative position, said filler plug being moved and held against the filler opening to seal the same when said latch means is locked.

6. In an electric steam iron of the type having a boiler with a recessed filler funnel at its top and a handle structure over the boiler, hingedly mounted for movement between a raised filling position exposing the filler funnel and a lowered operative position overlying the filler funnel, the combination with said handle structure and boiler of a combined unitary filler plug and releasable rotary latch means carried by said handle structure, said means including a manually operable knob and a shaft actuated thereby, and said filler plug comprising a yieldable annulus carried by the shaft in a downwardly projected position below the handle structure; and latch means on the boiler, cooperable with said rotary latch means to lock the handle structure in operative position, said filler plug being moved and held against the filler funnel to seal the same when said latch means is locked.

7. In a steam iron, a body including a boiler having a filler opening; a handle structure hinged with respect to the body for movement between a raised, boiler-filling position and a lowered operative position; a stopper for the filler opening, non-resiliently carried by the handle structure to seal the filler opening when the handle structure is in operative position; and releasable means for latching the handle structure in opera-

tive position, said means including cooperable parts on the body and handle structure, disposed closely adjacent and around the filler opening and stopper respectively whereby minimum tolerances can be maintained therebetween to provide a satisfactory latching and sealing action.

8. In a steam iron, a body including a boiler having a filler opening; a handle structure hinged with respect to the body for movement between a raised, boiler-filling position and a lowered operative position; a stopper for the filler opening, non-resiliently carried by the handle structure to seal the filler opening when the handle structure is in operative position; and releasable means for latching the handle structure in operative position, said means including cooperable parts on the body and handle structure, disposed closely adjacent and straddling the filler opening and stopper respectively whereby minimum tolerances can be maintained therebetween to provide a satisfactory latching and sealing action.

9. In a steam iron, a boiler having a filler opening; a stopper for the filler opening; a handle structure; means hingedly mounting the handle structure on the boiler for movement between a raised filling position and a lowered operative position; and manually releasable means for latching the handle structure in lowered position, including a mounting for securing the stopper on the handle structure to seal the filler opening when the handle structure is latched in lowered position, said latching means being disposed around the stopper mounting when the handle structure is latched.

10. In a steam iron, a boiler having a filler opening; a handle structure; means hingedly mounting the handle structure on the boiler for movement between a raised filling position and a lowered operative position; means for latching the handle structure in lowered position, including a manually operable knob on the handle structure and a member actuated by the knob, extending from said structure toward said filler opening; a stopper for said filler opening; and means mounting the stopper on the latch member whereby latching of the handle structure in lowered position moves and holds the stopper against the filler opening to seal the same.

11. In a steam iron, a boiler having a filler opening; a handle structure; means hingedly mounting the handle structure on the boiler for movement between a raised filling position and a lowered operative position; means for latching the handle structure in lowered position, including a manually operable knob on the handle structure and a rotary shaft actuated by the knob, extending from said structure toward said filler opening substantially along the axis of the opening when the handle structure is in lowered position; a stopper for said filler opening; and means non-yieldably mounting the stopper on the lower end of the latch shaft whereby latching of the handle structure in lowered position moves and holds the stopper against the filler opening to seal the same.
